[57] CLAIM

The ornamental design for a leash for readily securing a pet, as shown and described.

DESCRIPTION

FIG. 1 is a perspective view of the leash for readily securing a pet showing my new design, where the looped handle snaps open and closed for securing a pet to a fixed object; FIG. 2 is a left hand view of the end of a leash for readily securing a pet to be fastened to the pet.

FIG. 3 is a front view of the end of FIG. 2.

FIG. 4 is a right hand view of the end of FIG. 2.

FIG. 5 is a back view of the end of FIG. 2.

FIG. 6 is left hand view of the handle end of a leash for readily securing a pet.

FIG. 7 is a front view of the handle end shown in FIG. 6.

FIG. 8 is a right hand view of the handle end of FIG. 6; and, FIG. 9 is a back view of the handle end of FIG. 7.

FIGS. 2-9 shown broken away for convenience of illustration.

The broken line showing of environment in FIG. 1 is for illustrative purposes only and forms no part of the claimed design.
